*Inventor:
Nathan Richardson*

United States Patent Office.

NATHAN RICHARDSON, OF GLOUCESTER, MASSACHUSETTS, ASSIGNOR TO
"THE RICHARDSON MILL COMPANY," OF SAME PLACE.

Letters Patent No. 78,830, dated June 9, 1868.

IMPROVED ICE-CRUSHER.

The Schedule referred to in these Letters Patent and making part of the same.

TO ALL WHOM IT MAY CONCERN:

Be it known that I, NATHAN RICHARDSON, of Gloucester, in the county of Essex, and State of Massachusetts, have invented certain new and useful Improvements in Ice-Crushers; and I do hereby declare that the following is a full and exact description thereof, reference being had to the accompanying drawings, and to the letters of reference marked thereon.

The nature of my invention consists in combining with the crushing-wheels of an "ice-crusher," a number of vibrating-teeth or spikes, which serve to split the larger pieces of ice, so that the teeth of the crusher may grapple them.

To enable others skilled in the art to make and use my invention, I will proceed to set forth the description and use. In the drawings—

Figure 1 represents an elevation of the ice-crusher, a part of the hopper being broken out to show the internal parts.

Figure 2 represents in side elevation a portion of the gear.

Figure 3 is a side elevation of one of the cams, shown in front elevation D D' in fig. 1.

That portion of my machine which works as a crusher, including the toothed wheel I, and all below it, is covered by patent granted to me, June 3, 1862, and numbered 35,472, and as it is fully described in that patent, it is not necessary to describe those parts now. I will therefore confine myself to the description of the new parts of the machine, namely, the splitting-spikes M M, &c., and the operating-device connected therewith.

M M M, fig. 1, are a series of pointed spikes or teeth, connected to a solid heavy bar, H H, the end of which rests upon the cams D D'. This bar, and consequently the teeth or spikes M M, are free to vibrate up and down, being guided by the bar K K, and being operated by the cams D D'. The shape of these cams is shown in fig. 3. P P is a shaft, to which the cams D D' and pinion C are attached. The cams D D' are operated by the pinion C, which meshes into the main wheel N.

Having thus described my invention, I will now proceed to set forth my claim.

What I claim as my invention, and desire to secure by Letters Patent, is—

In an ice-crushing mill, the vibrating-teeth or spikes M M M, &c., operated by the cams D D', or their mechanical equivalents, in combination with the toothed crushing-wheels, substantially as described and for the purpose set forth.

NATHAN RICHARDSON.
